US00D605403S

(12) **United States Design Patent**
Santamarina et al.

(10) **Patent No.:** **US D605,403 S**
(45) **Date of Patent:** **** Dec. 8, 2009**

(54) **TOOL CONTAINER**

(75) Inventors: **Aland Santamarina**, Columbia, MD (US); **Gabriel E. Concari**, Eldersburg, MD (US)

(73) Assignee: **Black & Decker Inc.**, Newark, DE (US)

(**) Term: **14 Years**

(21) Appl. No.: **29/304,011**

(22) Filed: **Feb. 22, 2008**

(51) LOC (9) Cl. **03-01**

(52) U.S. Cl. **D3/294; D3/905**

(58) Field of Classification Search **D3/273, D3/294-295, 905; D8/87, 105, 107; 7/138, 7/165, 168, 170; 206/349, 372-373, 379**

See application file for complete search history.

CLAIM

The ornamental design for a tool container, as shown and described.

DESCRIPTION

FIG. 1 is a top perspective view of the tool container of the present disclosure;

FIG. 2 is a bottom perspective view of the tool container of FIG. 1;

FIG. 3 is a bottom plan view of the tool container of FIG. 1; FIG. 4 is a front elevation view of the tool container of FIG. 1; FIG. 5 is a right side elevation view of the tool container of FIG. 1;

FIG. 6 is a top plan view of the tool container of FIG. 1;

FIG. 7 is a left elevation side view of the tool container of FIG. 1; and,

FIG. 8 is a rear elevation view of the tool container of FIG. 1. The portions of the drawings shown in broken lines illustrate environment and form no part of the claimed design.

1 Claim, 4 Drawing Sheets
